GARMENT CONSTRUCTION

John B. Ransom, Rensselaer, N. Y., assignor to
 H. D. Bob Company, Inc., New York, N. Y., a
 corporation of New York

Application December 13, 1934, Serial No. 757,354

8 Claims. (Cl. 2—115)

This invention relates to the seam construction of garments and more particularly to shirts and method of attaching sleeves thereto.

In the ordinary construction of shirts in which sleeves are inserted by the single needle method, the inserting is done by joining the sleeve to the shirt in one operation and stitching down the underseam in the second operation. This has been a very unsatisfactory method due to the uneven width of the seam so produced. To make a good seam by this method requires an experienced operator who must carefully roll in the raw edge of the sleeve after it is run in, taking care to get it uniform in width before stitching it down. This is a slow process due to the fact that only a short edge portion can be turned and sewn at a time, and adds considerable to the cost of production. An uneven seam of this character is unsightly and brands the garment as one of inferior quality. An even seam on the other hand gives the garment a custom-made appearance and enhances its value and marketability.

It is accordingly among the objects of this invention to provide an improved seam construction and a method whereby this construction may be secured.

An important object is to provide a method for attaching the sleeve to a shirt with a minimum amount of skilled labor.

Another object is to provide a method for making finished seams in garments and especially at the armhole in which only one row of stitching is visible on the outside of the garment.

A further object is to provide a method for attaching a sleeve to the body of a garment so that when the seam is stitched it is not necessary to roll under or hem any edge.

These and other objects which will be apparent from the sequent description are all embraced within the scope of this invention, which is illustrated as to a preferred embodiment in the accompanying drawing which should not be considered as a limitation thereof but simply as illustrative and in which:

Figure 1 is a front view of a portion of a completed garment specifically illustrated as a shirt;

Figure 2 is a plan view of a sleeve with the upper edge hemmed;

Figure 3 is a section view along the line 3—3 of Fig. 2, looking in the direction of the arrows;

Figure 4 is a top plan view showing a portion of the garment with the sleeve attached by one row of stitching;

Figure 5 is an inverted section view along the line 5—5 of Fig. 4;

Figure 6 is a sectional view similar to Fig. 5, showing an intermediate operation; while Figure 7 is a sectional view along the line 7—7 of Fig. 1.

This invention relates broadly to the seam construction of garments and especially to shirts and the method of attaching the sleeves thereto. It comprises a plurality of sewing operations in which the body of the garment is first assembled by joining the front panels to the yoke and the back panels to the yoke. The sleeve is prepared for insertion by sewing a hem across the top of the sleeve, after which it is attached to the body of the garment by stitching it along the armhole opening. One more stitching is then employed to complete the seam for the attachment of the sleeve and involves stitching down the hemmed edge to the garment body.

By following the above steps the sleeve may be readily attached to the shirt with a minimum number of operations which are readily performed without the necessity of employing skilled workmen, since all of the operations are very simple sewing steps. As a result of this process it is possible to construct shirts more rapidly and expeditiously, with a marked reduction in the cost of producing a completed garment of good appearance.

Referring now more specifically to the preferred embodiment as illustrated in the drawing, attention is directed to Fig. 1, which is a front view of a major portion of the completed garment. The garment illustrated as a shirt and designated generally as 2 includes two front panels 4 and 6, a yoke 8 and a back 10 (see Fig. 4). In constructing a garment according to the teachings of this invention, the first steps comprise attaching the back to the yoke by a seam 11 and joining each of the front panels to the yoke by seams 5 and 7 to provide a structure illustrated generally in Fig. 4.

The first operation in connection with attaching the sleeve to the body of the garment is the formation of a hem along the top of the sleeve on the right side of the material, as shown in Fig. 2. This is accomplished by turning over the upper edge of the sleeve 12 and stitching down the turned over portion at 14 to form a hemmed edge 15. The rough edge 16 need not be turned under, since it is later hidden in the further construction of the garment. By hemming the upper edge of the sleeve before the sleeve is inserted in the garment it is not later necessary to turn under any edge while the sleeve is being sewed.

into the garment or after it is in place, thereby obviating the slow work that is ordinarily necessary when sleeves are attached to a garment in the normal fashion in which it was necessary not only to sew the sleeve into the garment, but also to simultaneously or subsequently turn under one or more edges, which are operations requiring the exercise of considerable skill and very time consuming.

10 After the top edge of the sleeve has been hemmed, as described above and illustrated in Figs. 2 and 3, the sleeve is laid flat on the work table with the hemmed edge up. The body of the garment is then placed with the right side down on top of the sleeve in the position illustrated in Fig. 4, with the hemmed edge 14 arranged to follow the contour of the armhole edge 18. The sleeve is then attached to the garment by a single row of stitching 20 along the 15 unfinished edge of the armhole 18. This row of stitching 20 is gauged by the edge of the armhole and the hemmed edge 15 and may be any suitable distance from the hemmed edge 15 or the stitches 14, but is preferably about one-half 20 inch.

Fig. 5 illustrates a cross section along the line 5-5 except that the sectional view is inverted to correspond with the view in Fig. 7. From this figure it will be noted that the sleeve 12 is closely 30 associated with the body of the shirt and with a portion of the sleeve projecting beyond the unfinished edge 18 of the armhole. The turned over portion of the sleeve forming the hem 15 and the garment body are both on the same side 35 of the sleeve. In both Figs. 4 and 5 the right or outside of the sleeve is against the right or outside of the garment body.

After the seam stitching 20 has been completed for the length of the armhole, the sleeve's 40 position with reference to the garment is changed as by pivoting it about the seam stitching 20. This operation is illustrated in Fig. 6, which shows the sleeve being pivoted about the stitching 20. The sleeve is given a turn of about 180°, 45 after which it assumes the position shown, somewhat enlarged, in Fig. 7. The body of the shirt 6 continues to the armhole opening as limited by the stitching 20 and then is folded under itself. The stitching 20 is normally invisible from the 50 outside of the shirt and there is only a slight break 22 at the folded edge of the body portion of the garment. The turned under edge 16 of the sleeve 12 is between the sleeve and the body of the shirt 6 and, therefore, unexposed.

55 When the sleeve has been placed in the position generally illustrated in Fig. 7, the final sleeve inserting operation of stitching down the hemmed edge of the sleeve is performed by sewing an inner row of stitches 24, which completes 60 the armhole seam. It is usually preferable to make seam stitchings 20 and 24 while the inside of the garment is up.

After the sleeves have been attached to the garment along the armholes, the under seams of 65 the sleeves and the side seams joining the front panels with the back may be completed by a single stitching begun at either the bottom of the shirt or at the cuff and continued for the entire length of the seam 26. If desired, the underarm 70 seam may be made at an earlier stage of construction, even before the sleeve is attached to the garment, but the foregoing method is preferable. The garment is now ready for completion in the conventional manner by attaching a 75 collar 28 or neckband to the neck opening 30,

finishing the inner edges of the front panels for buttons and buttonholes, attaching cuffs, etc.

In one of the preferred modifications as described above the first operation on the sleeve involved hemming the top of the sleeve by a single reverse fold followed by stitching down the folded edge. A somewhat neater edge may be secured by overedging or a double fold hem in which no rough edge is visible at the top of the sleeve before insertion. Instead of the single or double fold hems above described one may use an extra strip of material such as a tape to bind the rough edge. The binding tape if it has rough edges may have these edges turned under before or as the tape is sewed to the top of the sleeve. 15 All of the foregoing methods cover the raw edge at the top of the sleeve before insertion into the garment proper and for convenience in expression are considered to come within the terms of hem, or hemming.

20 It will thus be seen that this invention involves a new and useful method for seam construction, of particular utility in attaching the sleeves to the body of the shirt, as well as the resulting structure. It comprises broadly three operations, 25 hemming the top of the sleeve, running in the sleeve preferably with a folder to give an exact seam on the total bell of the sleeve and stitching down the hemmed edge.

The foregoing operations produce a garment 30 construction in which the armhole seam includes three rows of stitching, although more could be used, if desired, one row of stitching 24, which may be termed an inner row, passing through three thicknesses of material, another row of 35 stitching 14 passing through two thicknesses of the same piece of material, and a third or outer row of stitching 20 through two layers of different pieces of material.

Having thus described my invention with reference to a preferred embodiment, what I claim is:

1. In the process of garment construction, the steps comprising hemming the top of the sleeve, sewing the sleeve into the armhole with the right 45 faces together and stitching down the hemmed edge to the garment.

2. In the process of shirt construction, the steps of assembling the front, yoke and back, hemming the top of the sleeve, sewing the sleeve 50 into the armhole with the right faces together and stitching down the hemmed edge to the garment.

3. In a process of garment construction, the steps comprising assembling the body of the garment, hemming the top of the sleeve, arranging the sleeve across the outside of the garment, sewing the sleeve into the armhole with the right 55 faces together and stitching down the hemmed edge to the garment.

4. In a process of garment construction, the steps comprising assembling the body of the garment, hemming the top of the sleeve, arranging the sleeve across the outside of the body, sewing the sleeve into the armhole, folding the sleeve 60 away from the body and stitching down the hemmed edge to the body.

5. In a process of shirt construction, the steps comprising joining the front panels to the yoke, joining the back to the yoke, hemming the top 70 of the sleeve, laying the sleeve across the outside of the shirt with the hemmed edge at the armhole, sewing the sleeve into the armhole, folding the sleeve away from the body of the shirt and stitching down the hemmed edge to the shirt.

6. In a process of shirt construction, the steps comprising joining the front panels to the yoke, joining the back to the yoke, hemming the top of the sleeve, laying the sleeve across the outside 5 of the shirt with the hemmed edge at the arm-hole, sewing the sleeve into the armhole, folding the sleeve away from the body of the shirt, stitching down the hemmed edge to the shirt and sewing the underarm seam.
- 10 7. A shirt construction for attaching the sleeves to the underside of the body of the shirt, an inner seam in which the threads pass through all the body and sleeve layers and an outer seam in which the threads pass through only the sleeve and a turned under layer of the body so as not to be visible on the outside of the shirt and producing a finished edge at the last named seam.
8. In a garment construction, a finished arm-hole seam comprising three rows of stitching, one row of stitching through the body and two thicknesses of sleeve forming a hem, another row of stitching through two thicknesses of the sleeve to form a hem and the third row of stitching through one turned under thickness of the body and one thickness of the sleeve. 5 10
